FISHING LURE

Edward S. Niewiarowicz, River Rouge, Mich.

Application December 21, 1953, Serial No. 28,164

Term of patent 14 years

(Cl. D31—4)

Fig. 1.

Fig. 2.

To all whom it may concern:

Be it known that I, Edward S. Niewiarowicz, a citizen of the United States, residing in River Rouge, county of Wayne, and State of Michigan, have invented a new, original, and ornamental Design for a Fishing Lure, of which the following is a specification, reference being had to the accompanying drawing, forming part thereof.

In the drawings:

I claim:

The ornamental design for a fishing lure, substantially as shown.
